UNITED STATES PATENT OFFICE.

BARTOLOMEO AMENDOLA, OF SAN FRANCISCO, CALIFORNIA.

RAILWAY BRAKE.

Application filed November 15, 1921. Serial No. 515,281.

To all whom it may concern:

Be it known that I, BARTOLOMEO AMENDOLA, a citizen of Italy, residing at San Francisco, in the county of San Francisco, 5 State of California, have invented a new and useful Railway Brake, of which the following is a specification in such full and clear terms as will enable those skilled in the art to construct and use the same.

This invention relates to a mechanical brake for railway trains and cars and is intended to act directly upon the car axle to check the speed of the train or to completely stop the train whenever necessary.

Other objects of the invention will appear as the description proceeds.

An embodiment of the invention is shown in the accompanying drawings in which the same reference numeral is applied to the 20 same portion throughout, but I am aware that there may be modifications thereof.

Fig. 1 is a plan view of the complete apparatus, showing it as it appears when the train is running.

Fig. 2 is a plan view of the complete apparatus showing it in operation with the axle most fully acted upon by the brake.

Fig. 3 is a vertical sectional view of the casing supporting one of the brake pins.

Fig. 4 is a plan view of one of the supporting plates carrying the brake pins.

Fig. 5 is a longitudinal sectional view of the plate shown in Figure 4.

Fig. 6 is a transverse sectional view of the plate shown in Figure 4.

Figure 7 is an end view of the plate shown in Figure 4.

Fig. 8 is a side elevation of the complete apparatus showing the means for operating it, the brake being released from the car axle.

Fig. 9 is a side elevation of the complete apparatus showing the brake applied to its fullest extent.

Fig. 10 is a front elevation of the casing carrying one of the brake pins.

Fig. 11 is a view in elevation of the casing carrying one of the brake pins, looking in the opposite direction from Figure 10.

Fig. 12 is a plan view of the levers for applying the brake.

Fig. 13 is a view in side elevation of the casing which carries the brake point.

Fig. 14 is an end view of the casing carrying the brake point.

Fig. 15 is a side elevation of the wheel upon which the brake directly acts.

Fig. 16 is a transverse sectional view of the wheel upon which the brake point acts.

Fig. 17 represents a side elevation of one form of levers for operating one of the brake shoes.

Fig. 18 is a side elevation of one of the spiral springs for holding one of the brake shoes in the intermediate position, and

Fig. 19 is a side elevation of a portion of the frame carrying the brake apparatus adjacent the car axle.

In the figures only the central portion of the car axle is shown and the car truck is 70 completely omitted, the truck forming no part of the present invention.

This invention is installed in a frame which is supported from the car truck in any suitable manner, and consists of four 75 frame members 19" connected together by four tie rods 35 at one end, and by two tie rods 36 at the other end. Two plates 19' connect the frame members 19" together at one end, while two plates 19 connect the 80 frame members 19" at the other end.

In addition to the foregoing frame there is an additional frame consisting of four longitudinally extending members 27. These frame members 27 are connected together at their ends by transversely extending frame members 27', 28', and at one end they carry angles 37 through which the stay rods 36 pass. Four vertical plates 28 connect the side members 27 as illustrated in 90 Figures 8, 9 and 19.

The car axle is indicated at 13 and it has a pair of boxes 16 clamped thereon by means of the bolts 17. Between these two boxes there is the cog wheel 14 which is secured to 95 the axle by means of the keys 18.

The casing carrying the brake point 7 is supported from the arms 8, 8' of which there are four at the top and bottom of the rectangular casing 1. This casing is slotted at 100 the front to permit the brake point or shoe 7 to project therethrough, and it is slotted at the sides as indicated at 3' to permit the arms 5' of the brake shoe supporting plate to project therethrough.

The brake shoe consists of a pointed body of metal somewhat like a heavy gear tooth, which is connected to the rectangular box 6, said box being slidable upon a pin 3 which extends through the casing 1. The rectan- 110

gular box 6 (see Figs. 3 and 13) has cheek pieces 6' to give it added strength and to form the top and bottom of the pocket of the shank 7' of the brake shoe 7. The brake shoe 7 has the supporting plates 7', 7" connected thereto which embrace the pin 3, and it is secured to the casing 6 by the pins 10, said shoe 7 extending through the opening 11.

At top and bottom the casing 1 is closed by means of the flanged plates 4 through which the pin 3 passes. At the back of the casing 1 there is a flanged plate 5 filling the opening into said casing, and there is a door 15 25 which may be opened when it is desired to remove the box 6 for renewing one of the brake shoes.

A cross bar 34 is connected to the two stay rods 35, and it has two lugs 33 projecting therefrom which pass over a pivoted rod 26. The rod 26 is pivoted at 26' on a plate 26" secured to the cross bar 27'. The rod 26 is curved and at its upper edge engages a slotted head 30' of a piston rod 30 which is operated by means of a suitable piston within the air cylinder 29. The rod 30 is also connected to a lever 31 pivoted at 31' which extends to the rod 39 for the operation of another brake on another truck.

The brake casing 1 is bolted to the plates 19" and is movable with the frame as a unit, the front and back of the casing 1 being enclosed by the plates 5, one of which is slotted to permit the brake shoe 7 to extend therethrough, and have extensions 23 with ears 24 at the opposite ends thereof which are connected together by means of the bolts 22.

Heavy spiral springs 20 connect the ends 5' of the plates for holding the brake shoe in the central position, and since the plates 5' can only move away from each other on account of the limitation of the slots in which they move—notice Fig. 8—any movement up or down of the brake shoe 7 will be resisted by said springs.

The plates for holding the brake points in the central position have shoulders 5" thereon to prevent them from moving longitudinally out of the slots 3' in the casing 1.

Another rectangular casing 2 oppositely placed with respect to the casing 1, is supported by four arms 9 pivotally mounted on the stay rods 36. The casing has four 55 projecting ears 8 which are connected to slots in the ends of the bars 9, and the opposite ends of the bars are slidably connected with the frame members 19" by means of bolts 9' which pass through slots 60 in the bars 9.

The casing 2 is substantially identical with the casing 1 except that its supporting ears extend at right angles to the supporting ears which carry the casing 1, and 65 it has the same kind of a projecting brake

shoe supported exactly the same as the brake shoe in the casing 1.

In operation when it is desired to stop the vehicle, the brake shoes are projected toward the pinion 14 by advancing the piston rod 30. The lever 26, will be then advanced from the position shown in Fig. 8 to the position shown in Fig. 9. This will push the frame members carrying the two casings to the position illustrated in Figure 9, and dependent upon the extent to which the frame is pushed forward will give a light or heavy braking effect. The fixed rods 16 act as a fulcrum for the levers 9 and cause the casing 2 to be advanced toward the 75 axle at the same time the casing 1 is advanced on the other side. If the brake shoes 7 are just slightly engaged with the pinion, the springs 20 will permit the brake shoes to be depressed and raised sufficiently 80 to permit the wheels to rotate with rapid retarding shocks given to the axle. If the frame is advanced to its fullest position it will project the brake shoes into the teeth 85 of the gear 14 with sufficient force to lock 90 the wheels and prevent them from turning.

It will be apparent that the invention may be made of any size desired depending upon the power required to apply the brake to the train, and the brake shoe or brake point 95 will be made of such size as is necessary to prevent undue wear thereon.

What I claim is as follows, but various modifications may be made in the construction shown in the drawings and above particularly described form, within the purview of my invention:

1. A brake for railway vehicles comprising the combination with an axle of a notched wheel carried thereby, a pair of casings on opposite sides of the axle, a brake shoe adapted to engage the notched wheel carried by each casing, springs for holding the brake shoes in a central position, and means to advance both casings and the brake shoes carried thereby toward the notched wheel for engagement therewith to stop the vehicle.

2. A brake for railway vehicles comprising the combination with an axis of a notched wheel carried thereby, a pair of brake supporting casings, a brake shoe carried by each casing, spiral springs for holding each brake shoe in a central position with respect to the apparatus, and a lever for shifting the brake shoes and casings toward the notched wheel on the axle 115 to bring the brake shoes into contact therewith to stop the vehicle.

3. A brake for railway vehicles, comprising an axle, wheels carried thereby, a notched brake wheel on the axle, a pair of frames supporting a brake shoe upon each side of said wheel, means to resiliently support each brake shoe and to allow it to 120 125 130

move resiliently in two directions, and means to advance the brake shoes toward the axle wheels carried by the axles to retard the rotation of the axle in either direction.

- 5 4. A brake for railway vehicles, comprising the combination with a car axle of a notched wheel carried thereby, a pair of casings on opposite sides of the axle, a brake shoe resiliently supported by each casing
10 and adapted to engage the notched wheel,

means to advance both of said casings toward the notched wheel so the shoes will engage the same, and rods upon which said brake shoes are vertically slidable to permit the brake to be applied to the axle regardless 15 of the direction of rotation thereof.

In testimony whereof I have hereunto set my hand this 8th day of November A. D. 1921.

BARTOLOMEO AMENDOLA.
